UNITED STATES PATENT OFFICE.

JOSEPH C. DANE, OF LA CROSSE, WISCONSIN, ASSIGNOR OF TWO-THIRDS
TO LUCINDA S. CARD AND FORREST J. SMITH, BOTH OF SAME PLACE.

CAR-BRAKE.

SPECIFICATION forming part of Letters Patent No. 292,793, dated February 5, 1884.

Application filed April 13, 1883. (No model.)

To all whom it may concern:

Be it known that I, JOSEPH C. DANE, of La Crosse, in the county of La Crosse and State of Wisconsin, have invented a certain new and useful Improvement in Automatic Car-Brakes, of which the following is a full, clear, and exact description, reference being had to the accompanying drawings, forming part of this specification.

10 This invention applies to car-brakes that are automatically applied to the wheels by the slowing up of the engine, causing the draw-heads to be forced inward, and by suitable connection to force the brakes against the 15 wheels. In this class of brakes there must be a provision to prevent the application of the brakes when backing the train, and this is where the chief complication comes in.

My invention is set forth in the claims.

20 Figure 1 is a top view, part of the car-floor being removed. Fig. 2 is a transverse vertical section at 2 2, Fig. 1. Fig. 3 is an enlarged detail perspective view of part of the brake-lever and the stirrup thereon. Fig. 4 is an enlarged horizontal section at 4 4, Fig. 7. Fig. 25 5 is an enlarged side elevation of the governor, and Fig. 6 is an end elevation of the same. Fig. 7 is a vertical longitudinal section at 7 7, Fig. 1. Fig. 8 is a detail perspective view of the lever-frame by which the push-bar is shifted transversely. Fig. 9 is a detail perspective view of the fulcrum-bracket by which the automatic brake-lever is connected to the bottom of the car-body. Fig. 10 is a side elevation 30 35 of the lazy-bar, showing its position when the cars are unloaded; and Fig. 11 is a similar view, showing the position of the bar when the car is loaded. Fig. 12 is an enlarged detail of part of the brake-lever and push-bar at rest. Fig. 13 shows the same in 40 action; Fig. 14, the same when the cars are running and being pushed by the engine, and Fig. 15 when the cars are being pulled forward at speed.

45 A A are the car-wheels, B the axle, C the truck, and D the car-body. An ordinary hand-brake shaft is shown at E, connected by the usual chain and rod, F, with any suitable or common brake system beneath the car.

50 G is the draw-head, which may have the

usual construction, except that from its inner end extends a rod, H, that passes through the lug I' of the push-bar I. The hole in the lug for the passage of the bar or rod H is made so large that the bar may be capable of the required transverse oscillation.

Upon the rod H are two springs bearing against the opposite sides of the lug I', the spring J bearing also against the inner end of the draw-head, and the spring K against a pin and washer or equivalent bearing, H', at the end of the rod H. Thus the lug I' has capacity for lateral movement along the rod H, (a very limited movement toward the draw-head, and a greater movement in the opposite direction, as the spring K admits of a much greater degree of contraction than the spring J.)

L is a lever fulcrumed to the car-body by means of a fulcrum-pin, M, and a bracket, N, secured to the bottom car-body timbers. The 70 lever L consists of two parallel bars secured together by the fulcrum-pin M, a push-pin, O, and two end pins, P, to which are secured the two rods R, that connect with the upper ends of the levers Q at both ends of the car-truck. 75 Thus when the lever L is acted on by the draw-head, the upper ends of the levers Q are drawn toward each other and the brakes applied to the wheels, the levers Q being connected to the brake-bars S, and the lower ends 80 of the levers connected by a rod, T. The push-rod I extends between the two parallel bars of the lever L. It has a shoulder, I², that engages the push-pin O in certain position and movement of the lever, and a hook, I³, at the 85 end that engages against the edge of the stirrup L' under certain circumstances, as herein-after mentioned, but more fully described in an application for patent filed herewith.

U is a bracket attached to the bottom of the 90 car, and forming the upper bearing of the lazy-bar V, to which the lever-frame W is fulcrumed. The lazy-bar ends at top in a pin, V', carrying a nut, V², the pin working in a hole of the bracket U, and the nut serving to limit the 95 descent of the pin in the bracket. Near the lower end of the lazy-bar is a slot, V³, through which passes a pin or stud, X', upon the bracket X, that is secured to the cross-timber C of the truck. The described manner of connect- 100

ing the lazy-bar to the bracket U, attached to the car, and the bracket X, attached to the truck, allows the independent movement of the car on the truck to go on without injury to the connections.

V⁴ is a fulcrum-pin extending horizontally and longitudinally from the outer side of the lazy-bar, and forming the fulcrum of the lever or shifter frame W. This frame has a horizontal arm, W¹, carrying a friction-roller, W², and a vertical arm, W³, forked at the upper end to embrace the pusher-bar I. Thus the movement of the frame W on its fulcrum causes the transverse movement of the free end of the pusher-bar.

I will now describe the governor. a is a sleeve, made in two parts to fit the axle B, and clamped thereto by bolts b. The bolts b form the pintles of toggle-arms c, that are hinged to similar arms, d, that are in turn hinged to the shield f, that has lateral movement upon the axle to and from the sleeve a. At the point of connection of the arms c and d are weights e, the pintle pins or bolts that connect the arms together serving also to connect the weights to them. The rotation of the axle serves to throw out the balls or weights e by centrifugal force and to draw the shield f to the sleeve.

g are springs, whose tendency is to draw the weights and arms into the position shown in Figs. 5 and 6, at which time the shield f is thrust away from the sleeve; and this is the position assumed by the parts when the cars are at rest.

The operation of the apparatus may be briefly described as follows: When the cars are at rest the parts are in the position shown in Figs. 5, 6, 12. If the engine then moves forward, the parts assume the position shown in 1, 2, 15. Then if the speed of the engine is checked, the brakes are applied, the position of the push-bar I and lever L being shown in Fig. 13. If, instead of pulling the cars, they are pushed, the bar I and lever L take the position shown in Fig. 14. Then if a pulling-force is applied to the car by another engine while the motion still continues, the catch or

hook I' engages the stirrup L', and that end of the lever is drawn forward, the rod H moves forward in the lug I', compressing the spring K. If, then, the pulling-engine backs onto the cars, the brake will not be applied, because the shoulder I² is beside the push-pin and not in position to engage it. The spring Y upon the pin or spindle tends to hold the frame W in such position that the shoulder I² of the push-bar will be in the position to engage the pin O, as seen in Figs. 1, 2, 15. When the cars come to a stand, the shield acts on the wheel W² on the arm W¹ and carries the free end of the push-bar into the position shown in Fig. 12.

It will be observed that the fork W⁴, forming the top of arm W³, is elongated to allow of the vertical motion of the car-body without disengaging the fork and bar I.

I claim—

1. The combination of the draw-head, push-bar I, connected to its inner end, horizontal lever L, fulcrumed upon one of the draft-timbers and connected to the brake-beams by the top rods, governor upon the axle, and a lever-frame having bearing on the vertical lazy-bar V, movably connected to the car body and truck.
2. The combination of a draw-head, rod H, springs J and K, push-bar I, lever L, fulcrumed to the car-body, lazy-bar connected to the car body and truck, lever-frame W, connected to the lazy-bar, and a governor with movable shield f, acting on the frame W, substantially as and for the purpose set forth.
3. The combination of a brake mechanism and a brake-governor consisting of the sleeve a, toggle-arms c and d, weights e, disk f, and spring or springs g, substantially as set forth.
4. The frame W, secured to the lazy-bar V, and having an arm, W¹, with elongated fork W⁴, engaging the push-bar I, substantially as set forth.

JOSEPH C. DANE.
